(57) **CLAIM**

The ornamental design for a crossfit gymnastics grip, as shown and described.

DESCRIPTION

FIG. 1 is a perspective view of an open configuration of my crossfit gymnastics grip.

FIG. 2 is a front view of the configuration of FIG. 1.

FIG. 3 is a back view of the configuration of FIG. 1.

FIG. 4 is a left side view of the configuration of FIG. 1.

FIG. 5 is a right side view of the configuration of FIG. 1.

FIG. 6 is a top view of the configuration of FIG. 1.

FIG. 7 is a bottom view of the configuration of FIG. 1.

FIG. 8 is a perspective view of a closed configuration of my crossfit gymnastics grip.

FIG. 9 is a front view of the configuration of FIG. 8.

FIG. 10 is a back view of the configuration of FIG. 8.

FIG. 11 is a left side view of the configuration of FIG. 8.

FIG. 12 is a right side view of the configuration of FIG. 8.

FIG. 13 is a top view of the configuration of FIG. 8; and, FIG. 14 is a bottom view of the configuration of FIG. 8.

The broken lines shown in the figures are for the purposes of illustrating environmental structure which form no part of the claimed design.

1 Claim, 7 Drawing Sheets
